US00D864890S

(12) **United States Design Patent** (10) Patent No.: **US D864,890 S**
 Henning (45) Date of Patent: ** Oct. 29, 2019

(54) **COMMUNICATION DEVICE**

(71) Applicant: **SONY MOBILE**
COMMUNICATIONS INC., Tokyo
 (JP)

(72) Inventor: **Simon Henning**, Lund (SE)

(73) Assignee: **SONY MOBILE**
COMMUNICATIONS INC., Tokyo
 (JP)

(**) Term: **15 Years**

(21) Appl. No.: **29/622,128**

(22) Filed: **Oct. 13, 2017**

(56)

(57) **CLAIM**

The ornamental design for a communication device, as shown and described.

DESCRIPTION

FIG. 1 is a perspective view of a communication device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a partially enlarged left side elevational view thereof along the lines 8-8 and 8'-8' of FIG. 4.

The broken lines depict environment that forms no part of the claimed design.

1 Claim, 6 Drawing Sheets
